US0D1066942S

(12) United States Design Patent (10) Patent No.: US D1,066,942 S
(45) Date of Patent: * Mar. 18, 2025

(54) SHOWER RACK

(71) Applicant: Tao Yang, Zhejiang (CN)

(72) Inventor: Tao Yang, Zhejiang (CN)

() Term: 15 Years

(21) Appl. No.: 29/970,390

(22) Filed: Oct. 28, 2024

(30) Foreign Application Priority Data

Jun. 19, 2024 (CN) 202421410082.2

(51) LOC (15) Cl. 06-04

(52) U.S. Cl. D6/525
USPC .....

(57) CLAIM

The ornamental design for a shower rack, as shown and described.

DESCRIPTION

FIG. 1 is a top, front and right-side perspective view of the shower rack showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is bottom, rear and left-side perspective view thereof. The broken lines in the figures depict portions of the shower rack and form no part of the claimed design.

1 Claim, 8 Drawing Sheets
